UNITED STATES PATENT OFFICE.

DAVID W. KLAU, OF NEW YORK, N. Y.

HEMMING MACHINE.

Application filed February 26, 1925. Serial No. 11,636.

To all whom it may concern:

Be it known that I, DAVID W. KLAU, a citizen of the United States, residing at 500 West End Avenue, New York city, in the county and State of New York, have invented new and useful Improvements in Hemming Machines, of which the following is a specification.

The general object of the invention is greatly to reduce the time, labor and handling required for sewing, hemming or binding the longitudinal edges of long pieces of material, such as material for roller shades. It is very desirable to reduce the amount of handling of material of this character, which heretofore has had to be run through the sewing machine, taken back, and run through again. By the present invention the length of material is hemmed on both edges at a single pass, by causing it to travel over a slotted table between two transversely spaced, relatively adjustable sewing machines adapted and driven in unison to operate simultaneously and equally on the two longitudinal folded edges. A particular object of the invention is to provide a simple and efficient organization of this character, wherein it is possible not only readily to adjust the spacing between the machines, but also to adjust instantly the operation of the machines, one relatively to the other, as for instance when a needle breaks, so that the machines will be in unison.

In the accompanying drawings forming part hereof:

Fig. 1 is a front elevation of a machine embodying the invention, a portion of the table being broken away to reveal parts in the slot, said parts being sectioned;

Fig. 2 is a plan view;

Fig. 3 is a vertical section on an enlarged scale, taken on the line 3—3 of Fig. 1; and

Fig. 4 is a plan view illustrating the operation of the machine.

The two sewing machines are conventionally illustrated.

The combined machine has a table 2 provided with a transverse slot 3 in its top, which slot is preferably continuous and extends substantially across the table, as shown, though this may be varied. The borders of the slot are desirably formed by transverse beams 4, as seen in Fig. 3, and on opposite sides of the slot suitable rabbeted guides 5 are provided.

Two reversely arranged sewing machines

6, their heads opposed to each other, are spaced apart transversely of the table at the region of the slot and guides, the bases 7 of the frames of these machines being mounted on the guides 5, so that preferably both of the machines can be adjusted toward and from a center to change the spacing between the sewing machines. Such adjustment is effected by sliding the machines along the guides over the slot, past graduations 8 placed along the edges of the slot. The selected spacing may be fixed by clamp screws 9 carried by yokes 10 bolted to the bases 7 of the machines and projecting downward through narrow slots 11 parallel with the slot 3, to embrace the beams 4.

The machines are driven from a common source of power, represented by a power receiving pulley 12 on a shaft 13. This shaft and a shaft 14 constitute a form of transverse shafting mounted beneath the table top, in bearings 15, 16 and 17. The two parts of the shafting, disposed one on either hand, as geared together by meshing gears 18 on their inner ends, rotate in opposite directions, and they drive the two machines through sprocket chains 19, 19 trained over upper and lower sprocket wheels 20 and 21, on the operating shafts of the machines and on the shafts 13, 14, respectively, the driving connections passing through the slot 3. Whereas the pulley 12 may be a friction pulley to take an ordinary belt as is customary in sewing machines, it is important that all parts of the driving mechanism between the common power source or intake and between the two machines be interconnected positively by meshing members causing the two machines to operate equally.

The sprocket wheels 21 are slidable lengthwise on the shafts 13 and 14, remaining in driven connection therewith by virtue of key-ways 22 in the shafts engaged by pins 23 in grooved hubs 24 of the wheels. The grooved hubs are engaged by shifter forks 25, which are bolted to the bases 7 of the sewing machines and project downward through the slot 3, so that when the machines are relatively adjusted to change the spacing between them, the driving connections are likewise automatically shifted along the transverse shafting.

Fig. 4 illustrates how the opposed sewing machines operate simultaneously on the opposite folded edges of a length of shade material *a*. The material is being fed in

the direction of the arrow and the dotted lines *b* represent the two lines of stitching which are being made at the same time in the hems. The necessity of absolutely equal speed and operation as between the two sides will be evident.

The split shafting 13, 14 having its two parts geared to rotate oppositely has the special advantage that it permits the use of standard sewing machines, the two machines being duplicates except that in one of the machines the feed must be reversed, so that when placed as shown both will feed in the same direction. Simpler shafting 15 might be employed but with less advantage. One of the advantages of connecting the machines with the split shafting by sprocket chains resides in the fact that the machines are free to be tilted endwise on the tables 20 toward the machines. This enables the chains to be slackened sufficiently to be shifted one or more teeth relatively to the sprocket wheels for restoring unison between the machines at any time.

25 A more limited relative adjustability between the sewing machines would be had if one only of the machines were made movable, but it is manifestly desirable that both be adjustable farther apart or nearer together, at opposite sides of the center of the width of the table.

The part of the slot 3 between the machines, where the material passes, is closed by a movable cover. This cover is best

made of a plate or plates 26, 26^a of the same 35 width as the bases 7 of the sewing machines and of such thickness as to be flush with the table top when they lie in the guides 5. It is intended that a sufficient number of these plates of different sizes be provided so that 40 the opening between the two sewing machines can be filled or approximately filled for any adjustment. The cover plates are connected to the base of one of the sewing machines, as by means of apertured lugs 27 45 projecting endwise from said base and pins 28 projecting downward from the plate 26 to enter these lugs. Similar lugs and pins 27^a, 28^a connect the plates 26 and 26^a, and so on, if there be other plates. 50

What is claimed as new is:

A machine of the character described, comprising a table having a transverse slot and bordering guides, two opposed sewing machines mounted on said table, relatively 55 shiftable along said guides, transverse driving means beneath the table comprising two parts rotating on parallel axes, meshing gears on the said parts causing them to rotate in opposite directions, means for driving 60 one of the parts, and similar positive driving connections comprising sprocket chains between the respective sewing machines and the respective parts below the table, said sewing machines being tiltable endwise toward said sprocket chains. 65

DAVID W. KLAU.
